Primary Examiner — Cynthia Ramirez*Assistant Examiner* — Llorellys M Martinez-Rivera(74) *Attorney, Agent, or Firm* — Michael A. Painter**CLAIM**

The ornamental design for a jewelry stone setting, as shown and described.

DESCRIPTION

FIG. 1 is a top perspective view of a jewelry stone setting showing my new design;

FIG. 2 is a top plan view thereof;

FIG. 3 is a left side elevation view thereof, the right side being identical thereto;

FIG. 4 is a cross-sectional view thereof, taken along line 4-4 in FIG. 2; and,

FIG. 5 is a bottom plan view thereof.
